CLAIM

The ornamental design for an outerwear as shown and described.

DESCRIPTION

FIG. 1 is a front view of an outerwear showing my new design;

FIG. 2 is a rear view thereof;

FIG. 3 is a left side view thereof;

FIG. 4 is a right side view thereof;

FIG. 5 is a front, left side, perspective view thereof;

FIG. 6 is a front, right side, perspective view thereof;

FIG. 7 is a rear, left side, perspective view thereof; and,

FIG. 8 is a rear, right side, perspective view thereof.

The broken lines immediately adjacent to the photographic area define the bounds of the claimed design and form no part thereof. The broken lines depicting the remainder of the outerwear form no part of the claimed design.

1 Claim, 8 Drawing Sheets
